CLAIM

The ornamental design for a microwave oven, as shown and described.

DESCRIPTION

FIG. 1 is a perspective view of the top, front and right side of a microwave oven showing my new design;

FIG. 2 is a front view thereof;

FIG. 3 is a top plan view thereof;

FIG. 4 is a bottom view thereof;

FIG. 5 is a right side view thereof;

FIG. 6 is a left side view thereof;

FIG. 7 is a rear view thereof; and,

FIG. 8 is a perspective view of the top, front and right side thereof with the lid in open condition.

The portion of the inside cavity of the microwave oven not shown in FIG. 8 forms no part of the claimed design.

1 Claim, 4 Drawing Sheets
